UNITED STATES PATENT OFFICE

2,408,269

THERMOSTATIC CONTROLLER FOR WATER TEMPERATURE

William R. Peterson, Chicago, Ill., assignor to Vapor Car Heating Company, Inc., Chicago, Ill., a corporation of New York

Application September 1, 1942, Serial No. 456,881

2 Claims. (Cl. 236—34)

1

This invention relates to an improved thermostatic means for controlling the flow of water in an engine cooling system, more particularly to a thermostatic valve mechanism adapted to be installed in the conduit through which the cooling water flows from the engine to the radiator.

This improved valve mechanism is so designed that it will respond only to predetermined changes in the temperature of the water stream, the valve normally remaining closed until its temperature rises above a predetermined level and then opening and remaining open until the temperature falls again.

The principal object of this invention is to provide a new and improved valve assembly which can be installed as a unit in the conduit between the engine and radiator.

Another object is to provide such an assembly in which the movable valve member is substantially balanced against water pressures both above and below the member, so that the position of the valve will normally be dependent entirely upon the water temperature.

Another object is to provide a valve of this type provided with a normally open passage permitting a limited flow of water through the valve at all times so as to equalize the water temperature both above and below the valve.

Another object is to provide such a valve embodying a thermostatic bellows having an auxiliary operating spring adapted to cause the valve to open in case of injury to the operating bellows. In other words the valve will fail, if at all, in open position.

Another object is to provide an improved valve of this type having a balancing bellows mechanism at the opposite side of the movable valve member from the thermostatic bellows, these two bellows mechanisms cooperating to keep the water pressures on the movable valve member substantially balanced at all times.

Another object is to provide such a valve assembly in which the movable members and bellows structures are substantially enclosed and protected at all times by an outer protective housing through which the water stream is permitted to circulate when the valve is open.

Other objects and advantages of this invention will be more apparent from the following detailed description of one approved form of the temperature operated assembly.

The accompanying drawing is a vertical central section through the valve assembly and a section of the conduit in which this assembly is

2

installed and through which the water stream flows.

The valve assembly forming the particular subject matter of this invention is housed within the upper bell-shaped portion 1 of the conduit member 2 rising from the engine block. As will be noted from the arrows, the water from this engine block flows or is forced upwardly through this conduit and thence through the elbow section 3 to a suitable connection with the upper portion of the radiator in which the water is cooled by exposure to the outer air.

The collar portion 4 at the bottom of elbow 3 is secured to the upper end 5 of conduit 1 by means of the bolts 6, there being an interposed gasket 7 to prevent leakage from the conduit.

The improved valve assembly is housed within and protected by a casing built up of metallic sections comprising a main upper section 8, a top section or cover 9, and a lower section 10. The upper end of section 8 is bent reversely on itself to form an outstanding collar portion 11 which is crimped about the outstanding collar 12 at the lower end of cover 9, this outstanding collar portion 11 being mounted within the circular groove 13 formed in the upper end of bell-shaped housing 14 and held therein by the upper elbow-section 3, thus supporting the entire valve assembly within the conduit. The lower end of casing 8 is bent inwardly and downwardly as indicated at 14 so as to terminate in a valve seat 15, against which the movable valve plate 16 is engaged to cut off the main flow of water through the conduit.

35 A small constantly open passage 17 is formed in disc or plate 16 so as to permit a continuous upward flow of water through the valve, even though the valve is closed. This prevents entirely cutting off the water flow while at the same time keeping the water both above and below the valve at substantially the same temperature.

The inner casing is completed by the lower shell or housing 10 having a closed bottom portion, an upper collar 18, which is secured around 45 the lower portion of upper shell 8, and which is provided with inlet openings 19 in the sides thereof for the flowing stream of water. This lower shell 10 encloses the lower balancing bellows or diaphragm hereinafter described.

50 It will be noted that the heated water from the engine first flows, as indicated by the arrows, around the lower portion of casing 10, thence inwardly through the inlets 19 and around the valve disc 16 when the same is open and through 55 the main valve opening into the upper chamber

20 within casing section 8 which houses the actuating thermostatic member. The water stream then flows through the various outlets 21 in the cover member 9 and thence out through the elbow-member 3 to the radiator.

The upper thermostatic bellows indicated as a whole at A is housed within the chamber 20 of upper casing section 8 and centered and suspended within this chamber by the upper disc 22 attached to the cover member 9 by bolt 23 and nut 24. The upper plate or disc 22 is connected with the lower disc 26 by the flexible corrugated metallic side bellows structure 25, the space within this bellows assembly containing a certain quantity of thermostatic fluid which is condensed at ordinary low temperature so that the interior of the bellows is partially exhausted. A hollow tubular member 27 open at both ends surrounds at its upper end the stud member 28 projecting downwardly from the upper end plate 22, while a similar tubular collar portion 29 projects centrally upward from lower plate 26 coaxially with the upper tubular member 27. A tubular sleeve 30 encloses the members 27 and 29 and is slideable on member 27 as the bellows structure elongates or contracts. A plurality of openings 31 are formed in the sides of tube 30 so that the space within the tubular members is in open communication with the space 32 within bellows 25.

A sleeve member 33 is attached at its upper end to the bottom disc 26 of the bellows, and attached at its lower end to the valve plate 16, thus serving as means for raising and lowering the valve plate 16 as the bellows A is contracted or expanded. Another sleeve or thimble member 34, closed at the bottom, is attached to the lower side of valve plate 16 and to the inner bottom surface of cup 40. This sleeve is in open communication at its upper end (through the valve plate) with the aligned tubes 29, 30 and 27 within the upper bellows structure. A portion of the thermostatic fluid within this bellows device is housed within the lower thimble member 34 so as to respond to temperature changes in the water below the valve plate while the upper bellows assembly responds to the water temperature in the upper chamber 20 above the valve plate. Since both of these water spaces are in continuous communication through the passage 17 in the valve plate 16, it will be seen that the thermostatic assembly A is responsive to substantially the same temperature at all times no matter which side of the valve this water may be located in. Since the interior of bellows 25 and the connected sleeve members is normally under a partial vacuum, the valve plate 16 will normally be held up in engagement with the valve seat 15. When the temperature of the water stream (and consequently the temperature to which bellows A is responsive) rises sufficiently, the thermostatic fluid will be expanded or vaporized and valve plate 16 will be forced downwardly away from seat 15. This will permit free passage of the water stream through the casing assembly from the engine to the radiator. When the temperature of this water stream falls sufficiently the thermostatic structure A will be contracted and the valve plate will again be lifted into engagement with its seat.

The lower balancing bellows B is housed within the lower casing section 10 and comprises a flexible diaphragm or bellows 35 anchored at its lower end 36 to the bottom of casing 10. The bellows B does not expand or contract readily in

response to changes in temperature, since it contains no thermal responsive fluid except the air trapped therein, at atmospheric pressure, at the time of sealing the bellows. This structure is held in place by the bolt 37 and nut 38. The upper end of the bellows 35 is secured at 39 to the cup member 40 which projects downwardly within bellows 35 and encloses the central thimble 34.

It will now be understood that the pressure of the water within the lower portion of conduit 1 tends to force the plate 16 upwardly against the seat 15, but at the same time this water pressure is exerted on bellows B tending to contract this bellows and pull the valve 16 downwardly. These two portions tend to counter-balance one another so that the movable valve member 16 will be controlled entirely by the thermostatic bellows A in the upper chamber.

At the same time, it will be noted that the water pressure in the upper portion of the conduit and in chamber 20 tends to contract the bellows 25 and thereby pull upwardly on the valve plate 16. The upper surface of the plate 16 (within its valve seat) is of substantially the same effective area as the opposed surface of bellows 25 so that here again the water pressures acting on the valve plate 16 will tend to counter-balance one another. The valve, therefore, will be normally controlled almost entirely by changes in the water temperature.

It will now be noted that an auxiliary spring 42 is coiled around the inner tubes between the upper plate 22 and lower plate 26 of the thermostatic assembly A. This spring is normally under some compression so that in the event that the upper bellows 25 should be perforated or otherwise fail, the spring 42 will expand and open the valve 16. This is essentially a safety device to assure that the main valve will fail in an open position, if at all, thereby preventing overheating of the engine.

It will now be seen that all parts of this assembly are protected and enclosed by the metallic casing and can be removed from the conduit or replaced as a unit.

The hole 17 in valve-plate 16 permits the escape of trapped air and by permitting a small continuous circulation of the water tends to equalize the temperature of the water, both above and below the valve, at all times.

The main valve will be normally closed at all low temperatures and the spring 42 tends to open the valve in case of failure of the thermostatic mechanism and thereby avoid overheating the water.

I claim:

1. In an engine cooling system, means for controlling the flow of water through a conduit leading from the engine to a radiator, comprising a valve-seat fixedly mounted in the conduit, a valve-plate movable from below to and from the seat to close or open the valve, an expansible bellows thermostat mounted in the conduit above the valve seat and attached to the upper side of the movable valve-plate, a thermostatic fluid in the bellows responsive to temperature changes in the water, a thermostatic fluid-containing receptacle projecting downwardly from the plate and connected through the plate with the thermostatic bellows so that the bellows thermostat will respond to temperature changes at both sides of the valve, and a second closed bellows member fixed at its lower end and secured to the lower face of the plate and having an end por-

tion of the same effective area exposed to the water pressure as the lower face of the plate, thus balancing the water pressures tending to raise the plate, and the said bellows thermostat having an end, the effective area of which exposed to the water pressure is substantially equal to the area of the top surface of the valve exposed to the water pressure, whereby the valve is substantially balanced against the water pressure.

2. In an engine cooling system, means for controlling the flow of water through a conduit leading from the engine to a radiator, comprising a casing having an upper section fixedly positioned in the conduit and provided with a reduced lower end forming a valve-seat surrounding an inlet opening and having outlet openings in the upper end, a valve-plate movable from below to engage the valve-seat and close the valve, a downwardly extending casing section enclosing the valve-seat and plate and provided with inlet openings in its side portion, an ex-

pansible bellows mounted within the upper casing section and attached at its movable lower end to the valve-plate, there being a quantity of heat-expansive fluid within the bellows so that it will function as a thermostat, a pressure balancing bellows mounted in the lower casing section and attached at its upper end to the valve-plate which end has the same effective area exposed to the water pressure as the lower face of the plate, the thermostatic bellows also having substantially the same effective end area as the exposed portion of the upper face of the plate whereby the valve is substantially balanced against the water pressure on opposite sides thereof, and a container communicating with the bellows thermostat and containing a thermostatic fluid therein, and extending to a position at the other side of the valve so that the said bellows thermostat will respond to temperature changes at both sides of the valve.

WILLIAM R. PETERSON.
